UNITED STATES PATENT OFFICE.

RAYMOND E. ROBINSON, OF OAK PARK, ILLINOIS.

BUCKET ELEVATOR.

1,289,270.

Specification of Letters Patent. Patented Dec. 31, 1918.

Application filed September 23, 1912. Serial No. 721,799.

To all whom it may concern:

Be it known that I, RAYMOND E. ROBINSON, a citizen of the United States, residing at Oak Park, in the county of Cook and 5 State of Illinois, have invented a certain new and useful Improvement in Bucket Elevators, of which the following is a full, clear, concise, and exact description, reference being had to the accompanying drawings, 10 forming a part of this specification.

My invention relates to bucket elevators for use in conveying different materials such as coal, sand, stone, etc., from a chute to different places as desired. My invention is 15 of such a nature that the bucket acts as a measuring element and is arranged with suitable apparatus which places the bucket in line with the end of a chute, so that the material falls directly into the bucket after 20 which it is conveyed to the desired point by suitable mechanism. At the time that the bucket is placed into a tilted position so as to receive the material, a gate which is disposed in front of the chute, is automatically 25 opened so that the material may fall into the bucket. My invention will be clearly understood by referring to the accompanying drawings in which:

Figure 1 is an end elevational view of the 30 bucket also showing the guides for the same as well as the tilting mechanism in proximity to the chute.

Fig. 2 is a sectional view taken at one side of the bucket and showing the relation of the 35 chute and the tilting mechanism with the bucket shown in dotted position.

Fig. 3 is an elevational view of a modified 40 tilting arrangement, although the bucket used here is of the same construction as the one shown in the previous figures.

Fig. 4 is a cross sectional view showing the rollers on the side of the bucket in section, and the bucket in a tilted position ready to receive a charge from the chute.

Fig. 5 is a more or less diagrammatic view 45 of an arrangement where there are two buckets employed and which are raised and lowered by the same hoisting mechanism.

Fig. 6 is an enlarged view of one form of 50 hoisting mechanism which may be employed in conjunction with my invention.

Fig. 7 illustrates the brake-band employed on the drum of the hoisting mechanism.

Referring now to Figs. 1 and 2, it will be 55 noted that there are vertical guides 1 and 2 which are disposed on each side of a bucket

3. These guides are arranged to be supported at the lower ends by plates 4, which are secured to any suitable support. There are two guides at each side of the bucket 60 which are formed by L shaped members 5, secured at the lower ends of the plates 4, and forming guiding channels 6 and 7. These guiding channels are in alignment with guiding channels 8 and 9, formed by L 65 shaped members 10 and 11, secured to a framework, which is pivoted on a rod 12, which is supported by side members 13 and 14. This tilting frame is constructed of standard steel shapes, and is provided with 70 plates 15, which are adapted to engage the rod 12. Secured to these plates are the members 16 and 17, 18 and 19, the member 19 being fastened to a plate 20, and to which is secured an L shaped member 21, a part of 75 which is bowed at 22 and is secured at its lower end to a plate 23, a member 24 being fastened to this plate and also to a plate 25 at the lower part of the tilting frame. The L shaped members 11 are secured to this 80 plate and are fastened at their lower ends by means of bolts 26 which pass through a spacing member 27 between the L shaped members 11. A similar spacing member 28 is fastened by means of bolts 29, which are 85 countersunk into one of the L shaped members so as to provide a clear path for the rollers on the bucket, which will be described hereinafter. The L shaped member 10 is fastened at its lower end to the member 17, as 90 shown, the member 17 also being secured to the plate 23. The L shaped members 10 and 11 are secured to the member 18, which is fastened to a plate 30, that is secured to the member 21. The frame construction just described is located at two sides and is connected by means of a gate 31, which is secured to the bowed sections 22. A chute 32 is arranged to direct coal or other material into the bucket after the tilting frame has 95 been brought into proper position, this bringing the bucket into line with the mouth of the chute. The bucket 3 is arranged at its lower end with a rod 33, which is supported by suitable members 34 secured to the 100 bucket. The outer ends of this rod carry flanged rollers 35, which are adapted to engage in the channels 9 of the tilting frame and the channels 7. Pivoted on each side of the bucket and to the rod 33 are two flat 105 bars 36, which at their upper ends are connected to a cross frame 37, carrying a U

shaped member 38, which is arranged to be engaged by suitable lifting mechanism to convey the contents of the bucket to any desired point. The bucket also has pivoted at 5 each side thereof rollers 39, which ride in the channels 8 and 6. These rollers are mounted upon rods 40, secured to the bucket. At the upper ends of the flat bars 36, there are secured two pins 40a, upon which the 10 rollers 41 are mounted, these rollers being arranged to ride in the channels 9 and 7. The tilting frame has at its upper portion an apron 42, which is frictionally secured upon a rod 43, extending between the two 15 side frames.

The plate or gate 31, has fastened to its upper end a cable 44, which passes over a sheave 45 and which has secured at its other end a weight 46. It is to be understood that 20 there is an arrangement such as this at the other side of the tilting frame.

Assuming that the bucket is being lowered from engagement with the channels 6 and 7, it will pass from these channels and into 25 engagement with the channels 8 and 9. As the bucket is being lowered into the tilting frame, this frame will swing about the pivot rod 12 until the weights 46 have reached the stops 47, the weight of the bucket being 30 sufficient to over-balance the combined weight of the weights 46. When the bucket has reached its lowermost position, which is shown by the dotted lines 48, it is in position to receive the material from the chute 35 32. As this material passes from the chute 32, the apron 42 is thrown into the position as shown in dotted lines, thus forming a bridge from the chute to the bucket. The material will almost fill the bucket, that is 40 to say, as shown by a dot and dash line 49, after which the hoisting mechanism is brought into play to turn the tilting frame from the dotted position to that shown by full lines and against the stop 49', and consequently the bucket from its tilted position 45 to a vertical position, as shown by the dotted lines 50, thus bringing the channels 8 and 9 into alignment with the channels 6 and 7, so that the hoisting mechanism can raise 50 the bucket and convey it to any desired point when it may be emptied by any suitable mechanism.

As the tilting frame is being turned about its pivot, the gate 31 serves to close the 55 mouth of the chute, and it is retained in this closed position owing to the weights 46, which are lowered from the stops 47, when the gate is brought into this closed position. As the bucket is raised, the apron 42, is 60 turned about the rod 43 into the position as shown in full lines. This result is secured by the members 51, secured to each side of the bucket and which engage the apron when the bucket is raised.

65 The arrangement just described makes it

very easy to load or fill a bucket from a chute, inasmuch as it dispenses with any intermediate mechanism which has heretofore been employed to fill an elevator bucket from a chute. The arrangement is very 70 simple and is not very liable to get out of order, consequently the maintenance expense is reduced to a minimum. This particular apparatus finds great utility in the handling of coal, sand, etc. In the modified 75 arrangement shown in Figs. 3 and 4, the bucket there employed is of the same construction as described in connection with Figs. 1 and 2. The particular arrangement for tilting the bucket is of a construction 80 such that the bucket is held in a certain position when it is filled, after which it is slightly lowered when it rights itself, so that it may be raised and conveyed to any desired point. To this end I have disposed 85 the channels 52 and 53, which are formed by the L shaped members 54 and 55, which may be suitably supported by any desired means. The lower ends of the L shaped members 55 have secured thereto a spacing 90 member 56. The lower ends of the L shaped members 54 are secured to a plate 57, which supports rounded L shaped members 58, and also the L shaped members 59, which are slightly bowed, and which are secured at 95 one end to a plate 60. The inclined L shaped members 61 are secured to this plate and are fastened to a plate 62. This arrangement provides a construction such that the L shaped members 59 are concentric with 100 the rollers 39, when in their lowermost positions, and bearing against the spacing members 56. There is a wide slot 63, between the L shaped members 59. The L shaped members 58 are cut away to conform to the shape 105 of this slot, as is also the plate 57. The plate 62 carries a rod 64, which has secured thereto an arm 65, on which an adjustable weight 65' is mounted. The rod 64 has secured thereto a tongue or switch 66, which is arranged so that it may direct the roller 35 into the channel formed by the L shaped members 61. To the left of these members, and secured to plates 60 and 67 there is arranged a slotted member 68 which is 110 adapted to guide a rod 69, this rod extending between this member and one which is similar to it, but on the opposite side of the bucket. A rod 70 is adapted to ride in the slot 63, and when the bucket is being tilted, 115 it is drawn from the right to the left end of the slot as shown. The rod 69 has secured to it as shown in Figs. 3 and 4, two cables 71, which engage sheaves 72 and also sheaves 73, and are secured to the gate 74, 120 which is adapted to normally close the mouth of the chute 76. The gate has secured to the top thereof cables 77, which pass over sheaves 78 and 79 and extend 125 downward and are fastened to the rod 70. 130

As the bucket is lowered, the rollers 35, engage the switches 66, so that these rollers ride in the inclined channels until these rollers get to the position as shown in full lines, 5 which is the filling position. As the bucket is being lowered it also engages the rod 69, which is normally at the top of the slots in the members 68. The rollers 39 and 41 are in the positions as shown in full lines; that 10 is to say they hold the bucket in a locked or tilted position. After the bucket has engaged the rod 69 and has been lowered into its tilted position, as shown by the dotted lines, the gate 74 will be lowered into the 15 position shown, so that the material may pass from the chute into the bucket. An apron 74' tightly hinged at 75' to gate is adapted to be thrown by the material to bridge the opening between the gate and the 20 bucket. After the bucket has been almost filled, it is lowered slightly by means of the hoisting mechanism or other means, so that the rollers 39 occupy the positions as shown in dotted lines. When the material has 25 passed into the bucket and the bucket is ready to be raised, it is first slightly lowered, so that the rollers 39 occupy the positions as shown in dotted lines, when the body of the bucket swings out of engagement with the rod 69 and the rollers 35 serve to push the rod 70 downward through the slots 63 and into the recesses 79. The bucket is rotated about the point that the rollers 39 occupy, when they are against the 30 spacing members 56, and as the bucket assumes an erect position, the gate 74 is gradually closed owing to the engagement of the rollers 35 with the rod 70, which is pushed to the right hand ends of the slots 40 63 and into the recesses 79. The bucket assumes an erect position owing to the weight of the material therein, and after it is in such position, the rollers 35 are in alignment with the L shaped members 54, so that the 45 bucket may be raised by the hoisting mechanism. As it is raised, the rollers 35 pass by the switches 66, that is to say, the switches swing about their pivots 64, after which these switches will resume the position 50 as shown in full lines, owing to the weight 65' associated therewith. The gate 74 has sliding engagement with the chute 76 by means of the L shaped members on each side of the chute which engage retaining members 81 on the gate. In fact any arrangement may be here used which will effectively keep the gate in sliding engagement with the mouth of the chute. As the 55 bucket is being raised, the apron 74' is brought into an upright position by the engagement therewith of the members 51 on the bucket.

This arrangement then provides mechanism by which the bucket is held in a locked 60 position while it is being filled, after which

it is slightly lowered when it assumes an erect position, so that it may be raised and conveyed to any desired point. When the bucket is being lowered for another charge it engages the rod 69 which has been 70 brought into the upper ends of the slots in the members 68, and as the bucket is lowered by its own weight, the gate is gradually opened.

Referring to Figs. 5, 6, and 7, I shall describe the mechanism for hoisting and lowering the buckets, also the arrangement whereby two buckets are employed in connection with the hoisting mechanism.

Fig. 5 shows more or less diagrammatically the guideways 82 and 83 for one bucket and the guideways 84 and 85 for the other bucket. These guideways are of the same construction as those described in connection with the Figs. 3 and 4. The buckets also are of the same construction, that is to say, there are three rollers on each side engaging guideways on each side and the buckets are arranged to be tilted at the lower ends of the guideways in order that they may be filled, and as one of said buckets is being held in such filling position, the other bucket is in a position at the top of its guideways, so that approximately two thirds of its load is emptied therefrom, 95 that is to say, when the bucket 86 is being filled or when it is held in its locking position such as described in connection with Fig. 4, the bucket 87 is in a position as shown in dotted lines, so that about two 100 thirds of its load is dumped out. When the bucket 86 is still lowered so that it may assume a vertical position, the bucket 87 of course is raised a certain distance, so that the remaining one third of the load will be 105 emptied out.

A cable 88 is attached to the bucket 86 and passes over sheaves 89 and 90, and over a sheave 91, and around a drum 92; and also around a sheave 93 and around another sheave 94, the other end of the cable being attached to the bucket 87, so that the raising of one of the buckets causes the lowering of the other bucket. The sheaves 91 and 93 are mounted upon rods 95 and 96 respectively, 115 which are secured at 97 and 98 to a bar 99, pivoted at 100. This arrangement provides a means for settling or lowering the buckets from their locked position such as described in connection with Figs. 3 and 4, so that 120 they may swing into their erect position after they have been filled with material. The action is as follows:

Assuming that the bucket 86 is in its locked position, and it has been filled with material, the weight thereof will serve to rotate the bar 99 about its pivot slightly, thus lengthening that part of the cable so that the bucket is lowered into a position such that it may swing into an erect posi- 125 130

tion so that it may be raised. While the bucket 86 is being filled, the rollers on the bucket 87, which engage the guideways 84 are engaging the curved portions 101, as shown in dotted lines, so that the charge in the bucket which has been previously filled is being emptied to the extent of two thirds of its contents. When the bucket 86 has been filled and is lowered slightly more owing to the arrangement in connection with the cable, the bucket 87 is lifted slightly more so that the remaining one third of its charge is emptied therefrom. The same operation takes place when the bucket 87 is being filled.

The drum 92 of the hoisting mechanism is mounted rigidly on a shaft 102, which is carried in bearings 103. Loosely mounted upon this shaft are gears 104 and 105 having clutch members 106 and 107, which are adapted to be engaged by the clutch members 108 and 109. The gear 104 meshes with a gear 110, secured to a shaft 111, and which carries another gear 112, which meshes with an idler 113, which in turn meshes with a gear 105. The shaft 111 is connected to a suitable source of power, so that the buckets may be raised and lowered as required. At the other end of the shaft 102 is secured a gear 114, meshing with a gear 115, carried upon a shaft 116, which is mounted in bearings 117. This shaft is threaded the greater part of its length, which threads are engaged by a weighted member 118, having an arm 119, extending outward in the path of two adjustable arms 120 and 121, mounted upon a rod 122, carried in bearings 123 and pivoted at one end to the rod 124, which in turn is pivoted at 125, and having its other end bifurcated and engaging the slot 126. The rod 124 has secured thereto a pin 127, which is adapted to engage a projection 128 on a bar 129, which is pivoted at 130, and is secured at the other end to a brake band 131, which passes around an extension from the drum 92. The clutch members 108 and 109 are splined at 132 to the shaft 102, so that when either one of the buckets is being raised or lowered, the drum 92 may be placed in operative relation with the source of power. For example, when the bucket 87 has been filled, it is raised by throwing the clutch member 108 into relation with the clutch member 106, so that the drum 92 is rotated in the direction indicated by the arrow, and the shaft 116 rotates so that the drum 119 is brought into engagement with the adjustable finger 120, when the drum is stopped by the clutch members 106 and 108 being thrown out of engagement and having the pin engage the projection 128 on the rod 129, so as to set the brake band tightly against the extension from the drum. The rod 122, is manually operated by means of a lever 133, which is pivoted at 134, and to

which is pivoted a link 135, that is pivoted at 136 to the bar 122. The lever 133 is operated to bring either of the clutch members 108 or 109 into operative relation with the companion clutch member. When the bucket 87 is being raised, the pin 127 is away from the point 128, so that the brake is released to permit the rotation of the drum. The drum may be caused to operate in the opposite direction by actuating the lever 133, thus causing the clutch members 107 and 109 to come into engagement and the drum will continue to rotate until the arm 119 engages with the finger 121, to move the bar 122, so as to bring the clutch members 107 and 109 out of engagement and at the same time set the brake.

It is to be understood, of course, that the mechanism for hoisting the buckets is more or less diagrammatically shown, and as a matter of fact any well known arrangement may be used to effect the desired result.

While I have herein shown and described the foregoing features of my invention, I do not wish to be limited to the precise details disclosed, as it is apparent to those skilled in the art, that modifications may be made without departing from the spirit and scope of my invention.

What I claim is:

1. In a bucket elevator, the combination of a bucket adapted to receive material, a chute, rollers on both sides of said bucket, two guideways on each side of said bucket for receiving said rollers, a U-shaped member pivoted to said bucket, rollers carried on the upper portion of said member and adapted to engage in said guideways, the lowermost rollers on said bucket being adapted to engage in the inclined portions of said guideways to tilt said bucket in front of the chute, and a gate for the chute controlled by said bucket.

2. In a bucket elevator, the combination of a bucket adapted to receive material, a chute, rollers on both sides of said bucket, two guideways on each side of said bucket for receiving said rollers, a U-shaped member pivoted to said bucket, rollers carried on the upper portion of said member and adapted to engage in one of the guideways on each side, the lower portions of said guideways being inclined and adapted to receive the lowermost rollers on said bucket to tilt the bucket in proximity to the mouth of the chute, and raising and lowering mechanism connected with said bucket.

3. In a bucket elevator, the combination of a bucket adapted to receive material, a chute, rollers on both sides of said bucket, two guideways on each side of said bucket for receiving said rollers, a U-shaped member pivoted to said bucket, rollers carried on the upper portion of said member and adapted to engage in one of the guideways on each

side, the lower portions of said guideways presenting a triangular path on each side for receiving the lowermost rollers on said bucket so that said bucket may be tilted 5 to receive a load from the chute and then brought into an erect position so that it may be raised, a gate controlled by said bucket, and hoisting mechanism connected with said bucket.

10 4. In a bucket elevator, the combination of a bucket adapted to receive material, a chute, rollers on both sides of said bucket, two guideways on each side of said bucket for receiving said rollers, a U-shaped member pivoted to said bucket, rollers carried on the upper portion of said member and adapted to engage in one of the guideways on each side, the lower portions of said guideways being of triangular shape thus 15 offering a path on each side of the bucket of a triangular conformation in which the lowermost rollers on the bucket are adapted to engage, such engagement resulting first to tilt the bucket to receive a charge from 20 the chute, and then to cause it to assume an erect position so that it may be raised, hoisting means connected with said bucket, and a gate for the chute controlled by said bucket.

25 5. In a bucket elevator, the combination of a bucket adapted to receive material, a chute, rollers on both sides of said bucket, two guideways on each side of said bucket for receiving said rollers, a U-shaped member pivoted to said bucket, rollers carried on the upper portion of said member and adapted to engage in one of the guideways on each side, the lower ends of said guideways being of a triangular shape, said ends being 30 adapted to guide the lowermost rollers on the bucket, so that said bucket will be tilted in front of the chute to receive a charge and then to be rotated into a vertical position, hoisting mechanism, and a gate controlled by said bucket.

35 6. In a bucket elevator, the combination of a bucket adapted to receive material, a chute, rollers on both sides of said bucket, two guideways on each side of said bucket 40 for receiving said rollers, a U-shaped member pivoted to said bucket, rollers carried

on the upper portion of said member and adapted to engage in one of the guideways on each side, the lower ends of said guideways being of a triangular shape, said ends 45 being adapted to guide the lowermost rollers on the bucket so that said bucket will be tilted in front of the chute to receive a charge and then to be rotated into a vertical position, mechanism for holding said bucket in such tilted position until it receives its charge, the weight of the charge causing the bucket to be lowered slightly when said bucket is rotated to a vertical position ready 50 to be raised.

55 7. In a bucket elevator, the combination of a bucket adapted to receive material, a chute, rollers on both sides of said bucket, two guideways on each side of said bucket for receiving said rollers, a lifting frame 70 pivoted to said bucket, rollers carried on each side of the upper portion of said member and adapted to engage in said guideways, the lower ends of said guideways having a triangular shape, said ends being 75 adapted to offer a path for the lowermost rollers on the bucket so that said bucket will be tilted in front of the chute to receive its load, means for holding said bucket in such tilted position until it receives its load, 80 the weight of the load serving to slightly lower the bucket when it assumes a vertical position ready to be raised, and a gate controlled by said bucket.

85 8. In a bucket elevator the combination of a guide frame, a bucket movably mounted in said frame, a downwardly inclined chute, said frame being provided adjacent the chute with a triangular bucket guiding way, devices carried near the bottom of the bucket 90 adapted to take the path of the triangular way to move the bottom of the bucket out of vertical alinement with the top thereof to tilt the bucket in front of the chute.

95 In witness whereof I have hereunto subscribed my name this 21st day of September, A. D. 1912.

RAYMOND E. ROBINSON.
